CLAIM

The ornamental design for pavement milling machine as shown and described.

DESCRIPTION

The patent or application file contains at least one drawing executed in color. Copies of this patent or patent application publication with color drawing(s) will be provided by the Office upon request and payment of the necessary fee.

1. Pavement milling machine

1.1 : Front

1.2 : Back

1.3 : Left

1.4 : Right

1.5 : Top

1.6 : Perspective

1.7 : Perspective

FIG. 1 is a front view of pavement milling machine; FIG. 2 is a back view thereof; FIG. 3 is a left view thereof; FIG. 4 is a right view thereof; FIG. 5 is a top view thereof; FIG. 6 is a first perspective view thereof; FIG. 7 is a second perspective view thereof; Bottom view is omitted because it is rare to be seen. The main design points of this design is shape; use of this design product is for pavement milling.
